Primary Examiner — Patricia Palasik(74) *Attorney, Agent, or Firm* — Davis Wright Tremaine LLP**CLAIM**

The ornamental design for a sorting or inspection apparatus, as shown and described.

DESCRIPTION

FIG. 1 is a front elevational view of the sorting or inspection apparatus;

FIG. 2 is a rear elevational view thereof;

FIG. 3 is a left side elevational view thereof;

FIG. 4 is a right side elevational view thereof;

FIG. 5 is a front, top, left side perspective view thereof;

FIG. 6 is a rear, top, right side perspective view thereof;

FIG. 7 is a top plan view thereof;

FIG. 8 is a bottom plan view thereof; and,

FIG. 9 is a front, top, right side perspective view thereof.

The broken lines in the drawings depict unclaimed environmental subject matter.
